UNITED STATES PATENT OFFICE

ANDREW ZICHY, OF NEW YORK, N. Y.

SHOTGUN LOADER

Application filed March 4, 1932. Serial No. 596,697.

The invention relates to shot gun loaders, and more particularly to a structure adapted to contain two loaded shells, and provided with a mechanism by which these shells may be automatically delivered into the barrel of a gun following the ejection of the discharged shell.

In duck hunting and in trap shooting it is sometimes desirable to rapidly reload a shot gun after it has been discharged, in order to permit the user to take an additional shot at a target before it is out of range. With the usual method of hand loading shot guns, the time interval required to recharge the gun is so great as to preclude this.

With the above conditions in mind, I have provided a shot gun loader which may be readily attached to the wrist of a marksman, thus leaving the hand free so as not to interfere with the handling of the gun. This loader is provided with two containers, within each of which a loaded shell may be supported in relation to a spring mechanism capable of forcing the shell longitudinally of the container and within the breech of the shot gun, this spring mechanism being normally restrained by a latch mechanism operative as a result of the proper locating of the container in relation to the gun.

It is desirable, in the loader of the invention, to so construct the spring restraining mechanism, and the latch mechanism controlling same, that one or both cartridges may be delivered to the gun according to the requirements of the moment.

The construction of the containers is such as to minimize likelihood of the loaded shells accidentally escaping from the container, the means used also being capable of being utilized to ensure accuracy in the alinement of a cartridge, both while it is within the container and while it is being delivered into the gun barrel.

In order to permit a rapid locating of the containers in relation to the breech of the gun, I provide a loader of the invention with one or more alining horns adapted to engage the sides of the breech of the gun barrel and aline the cylindrical containers of the loader with the bores of said barrel.

The invention consists primarily in a shot gun loader embodying therein two connected cylindrical shell containers, spring actuated means within each container and slidably in relation thereto, a latch mechanism operative upon said spring actuated means respectively, a latch controlling pin slidably mounted in relation to said containers and operative upon said latch mechanism, a spring operative upon said latch controlling pin having a normal tendency to position said pin forwardly of said containers, and means whereby said container may be attached to the wrist; and in such other novel features of construction and combination of parts as are hereinafter set forth and described, and more particularly pointed out in the claims hereto appended.

Referring to the drawing,

Fig. 1 is a side view of a loader embodying the invention in position adjacent the breech of a shot gun;

Fig. 2 is a plan view of the loader itself;

Fig. 3 is a front view thereof;

Fig. 4 is a section on the line 4—4 of Fig. 2, partly broken away and upon a larger scale; and

Fig. 5 is a section on the line 5—5 of Fig. 2 upon a larger scale.

Like numerals refer to like parts throughout the several views.

In each of the views of the drawing the loader is shown as being charged with loaded shells.

In the drawing, I have shown two hollow cylindrical containers, 10 and 11, open at the forward end and closed at the rear end. These containers converge toward their open ends so that the movement of shells positioned therein will be along the axis of the bores of the two barrels of a gun.

The containers 10 and 11 are supported by a frame 12 extending across the back of the loader and along the bottom thereof.

Within each container is a coiled spring, that in the container 10 being shown at 13, and that in the container 11, at 14. Associated with the spring 13 is a plate 15 freely slidable within the container 10 and having a tongue 16 projecting through a slot 17 in the side wall thereof toward the container

11. This slot extends well toward the open end of the container. The container 11 is provided with a plate 18 freely slideable therein and having a tongue 19 projecting 5 through a slot 20 in the side wall of said container and presented towards the container 10. The springs 13 and 14 have a normal tendency to move the plates 15 and 18 toward the open end of the respective containers.
10. Supported from the bottom of the plate 12 are a plurality of bearing brackets 21, which are spaced from the container sufficiently to afford clearance for the tongues 16 and 19. One of these brackets engages 15 both containers adjacent their open ends so as to ensure a proper spacing of the outlets at all times.

Mounted in the brackets 21 are two reciprocatory latch controlling pins 22 and 23 20 the forward ends of which are laterally extended as at 24 to ensure engagement of the pins with the shell ejecting mechanism of a gun. The rear end of each passes through an opening in a spring housing 25 supported by the back plate of the frame 12 and is enlarged so as to engage a spring 26 or 27 25 in said housing. These springs act respectively upon the latch controlling pins 22 and 23 with a normal tendency to position the ends 24 of said pins forwardly of the containers 10 and 11.

Engaging the tongues 16 and 19 are latch members 28 and 29 supported from the frame 12. These latch members prevent movement 35 of the plates 15 and 18 by the springs 13 and 14 until released by the actuation of the controlling pins 22 and 23 following the engagement of these pins with the ejecting mechanism of a gun. The latch members 28 and 40 29 may take any desired or suitable form. In the drawing, they are shown as being spring members adapted to be forced and held by cams on the pins 22 and 23 in the path of the tongues 16 and 19 when said pins 45 are in their forward position. Movement of the pins rearwardly of the containers will release said spring latch members and permit them to flex out of engagement with said tongues, and permit the plates 15 and 18 to 50 be moved towards the open ends of the containers by the springs 13 and 14. Such spring latch members may be flexed while engaged by the controlling pins to permit said tongues to pass them when loading shells in 55 the containers.

Two latch controlling pins 22 and 23 are used so that a shell from either or both containers may be charged into either or both gun barrels as required. By this arrangement, the containers may be selectively actuated to deliver a cartridge to a gun, the selection being entirely automatic as determined by the gun mechanisms.

Carried by the containers 10 and 11 is a 60 35 wrist strap 30 having a suitable attachment

means, as the buckle 31 by which the containers 10 and 11 and the parts appurtenant thereto may be secured adjacent the front of the wrist of a marksman in a position leaving the hand free to be used in the customary manner in handling a gun, while permitting the open ends of the containers 10 and 11 to be rapidly and accurately alined with the bore of each barrel of a gun.

To ensure the desired rapidity and accuracy 75 in the positioning of the containers as above described, I provide the forward outer end of each container with a laterally flared and transversely curved guide horn 32 or 33 which will embrace the breech of the gun in a manner to avoid the exercise of any great care 80 by the marksman in properly locating the containers.

The rim of a shot gun shell projects from 85 the body of the shell so that it is desirable to provide means which will have the two-fold function of avoiding possibility of shells falling from the containers 10 and 11 and holding such shells towards the open end of the containers in axial alinement with said 90 containers. This means, as shown, consists of inwardly directed friction tongues 34 formed of the material of the containers and engageable with a cartridge. These tongues 95 are yieldable to permit the passage of the rim of the cartridge when loading the container, or when said cartridges are being forced from the container by the plates 15 and 18 and the springs 13 and 14. Any desired number and arrangement of tongues 34 may be used to 100 secure the desired action.

The operation of the herein described shot gun loader is substantially as follows:—

The containers 10 and 11 are secured to 105 the front of the wrist by the strap 30 and buckle 31. Normally, the plates 15 and 18 are positioned adjacent the open end of said containers by the springs 13 and 14, the tongues 16 and 19 by engagement with the forward ends of the slots 17 and 20, preventing the plate from escaping from the containers.

A shell may be placed in each container by hand and forced inwardly thereof until the tongue upon the slideable plate is engaged with the latch member 28 or 29 co-operating therewith. The springs 13 and 14 are tensioned by this movement of the shell, and the spring is held under tension by the latch mechanism.

While the containers are thus being loaded, 120 the latch controlling pins 22 and 23 are maintained in their outermost position by the springs 26 and 27, as shown in Fig. 2.

After either or both barrels of a shot gun 125 have been fired, the marksman merely breaks the gun in the usual manner and ejects a shell which has been discharged. While the breech of the gun is exposed, he advances the arm carrying the loader of the invention, his hand passing over the top of the barrel. This mo 130

tion engages the horns 32 and 33 with the opposite side of the gun barrel, said horns guiding the open ends of the containers 10 and 11 so as to accurately aline the openings 5 therein with the bores of the gun barrels.

As the containers are thrust towards the breech of the gun in accurate alinement therewith, the ends 24 of the latch control pins abut against the shell ejecting mechanism of 10 the gun and are forced rearwardly thus releasing the latch member 28 or 29 or both according to whether one or both gun barrels have had a shell ejected therefrom.

As the tongues 16 and 19 are relieved from 15 the restraint of the latch members, the springs 13 and 14, which are fairly heavy, expand advancing the plate 15 and 18 toward the open end of the containers 10 and 11, moving the shells therein into the gun barrel by a 20 rapid movement thereof. While there is a sudden stoppage of the plates 15 and 18 by engagement of the tongues 16 and 19 with the forward ends of the slots 12 and 17, when this occurs, the shells will have attained sufficient momentum to be expelled from the 25 open end of the containers to ensure their proper positioning in the bores of the gun barrel.

By converging the containers 10 and 11 30 as shown, the shells are given a direction avoiding frictional engagement with the wall of the bore.

The friction tongues 34 normally prevent 35 the shells from falling from the containers, and ensure an axial alinement thereof with the containers. The springs 13 and 14 are sufficiently strong to overcome the resistance of said tongues to the movement of the shells and to force the rim of the cartridges or shells 40 past said tongues.

Immediately that the hand carrying the loader is removed from above the gun barrel, the latch control pins 21 and 22 resume their normal position and the loader is in condition 45 to receive shells as described preparatory to the next reloading of the gun.

The construction of the loader of the invention permits it to be attached to the wrist of the user in the manner above described in a 50 position where it will not interfere with the customary manner of handling a gun, and this position of the loader permits it to be quickly brought into the proper relation with the breech of the gun, after the gun has been 55 broken, to effect a reloading of the gun in the manner above described. In fact, this may be so rapidly done that, particularly in duck shooting, a gun, after both barrels have been discharged, may be reloaded and refired 60 before the ducks are out of range.

While the horns 32 and 33 are highly desirable, the user of the loader may become so adept that such horns need not be depended upon.

65 The rapidity with which the shells are

forced from the containers 10 and 11 permits the loading to be accomplished by a sharp quick movement allowing the hand to be immediately thereafter used in closing the breech of the gun.

70 It is not my intention to limit the invention to the precise details of construction shown in the accompanying drawing, it being apparent that such may be varied without departing from the spirit and scope of the 75 invention.

Having described the invention, what I claim as new and desire to have protected by Letters Patent, is:—

1. A shot gun loader embodying therein 80 two connected cylindrical shell containers, spring actuated means within each container and slideable in relation thereto, a latch mechanism operative upon said spring actuated means respectively, a latch controlling pin 85 slidably mounted in relation to said containers and operative upon said latch mechanism, a spring operative upon said latch controlling pin having a normal tendency to position said pin forwardly of said containers, and means whereby said container may be attached to the 90 wrist.

2. A shot gun loader embodying therein 95 two connected cylindrical shell containers, means engageable with the breech of a gun for alining said containers with the bores of a gun barrel, spring actuated means within each container and slideable in relation thereto, a latch mechanism operative upon said spring actuated means respectively, a latch controlling pin 100 slidably mounted in relation to said containers and operative upon said latch mechanism, a spring operative upon said latch controlling pin having a normal tendency to position said pin forwardly of said containers, and means whereby said containers may be attached to the 105 wrist.

3. A shot gun loader embodying therein 110 two connected cylindrical shell containers, outwardly projecting laterally flared and transversely curved horns secured at the opposite sides of said containers, spring actuated means within each container and slideable in relation thereto, a latch mechanism operative upon said spring actuated means respectively, a latch controlling pin 115 slidably mounted in relation to said containers and operative upon said latch mechanism, a spring operative upon said latch controlling pin having a normal tendency to position said pin forwardly of said containers, and means whereby said container may be attached to the 120 wrist.

4. A shot gun loader embodying therein 125 two connected cylindrical shell containers, each said container having a longitudinally extending slot through the wall thereof, a plate slidably mounted in each container having a tongue projecting through said slot, a spring acting upon said plate, a latch mechanism operative upon each of said projecting 130

tongues, a latch controlling pin slidably mounted in relation to said containers and operative upon said latch mechanism, a spring operative upon said latch controlling pin having a normal tendency to position said pin forwardly of said containers, and means whereby said container may be attached to the wrist.

5. A shot gun loader embodying therein
10 two connected cylindrical shell containers, friction tongues extending inwardly of each container whereby falling of a shell from the container is prevented, spring actuated means within each container and slidable in relation thereto, a latch mechanism operative upon said spring actuated means respectively, a latch controlling pin slidably mounted in relation to said containers and operative upon said latch mechanism, a spring operative upon
15 said latch controlling pin having a normal tendency to position said pin forwardly of said containers, and means whereby said container may be attached to the wrist.

6. A shot gun loader embodying therein
20 two connected cylindrical shell containers, friction tongues extending inwardly of each container whereby falling of a shell from the container is prevented, each said container having a longitudinally extending slot
25 through the wall thereof, a plate slidably mounted in each container having a tongue projecting through said slot, a spring acting upon said plate, a latch mechanism operative upon each of said projecting tongues, a latch
30 controlling pin slidably mounted in relation to said containers and operative upon said latch mechanism, a spring operative upon said latch controlling pin having a normal tendency to position said pin forwardly of
35 said containers, and means whereby said container may be attached to the wrist.

7. A shot gun loader embodying therein
40 two connected cylindrical shell containers, each said container having a longitudinally extending slot through the wall thereof, a plate slidably mounted in each container having a tongue projecting through said slot, a spring acting upon said plate, a latch mechanism operative upon each of said projecting
45 tongues, a plurality of latch controlling pins slidably mounted in relation to said containers and each operative upon a latch mechanism, a spring operative upon each of said pins and having a normal tendency to position
50 said pins forwardly of said containers, whereby the actuation of said pins by engagement with a gun barrel will cause the selective or simultaneous release of said latch mechanisms, and means whereby said container may be attached to the wrist.

8. A shot gun loader embodying therein
55 two connected cylindrical shell containers outwardly projecting laterally flared and transversely curved horns secured at the opposite sides of said containers, spring actu-

ated means within each container and slidably in relation thereto, a latch mechanism operative upon said spring actuated means respectively, a plurality of latch controlling pins slidably mounted in relation to said containers and each operative upon a latch mechanism, a spring operative upon each of said pins and having a normal tendency to position
70 said pins forwardly of said containers, whereby the actuation of said pins by engagement with a gun barrel will cause the selective or simultaneous release of said latch mechanisms, and means whereby said container may be attached to the wrist.

9. A shot gun loader embodying therein
80 two connected cylindrical shell containers, friction tongues extending inwardly of each container whereby falling of a shell from the container is prevented, each said container having a longitudinally extending slot
85 through the wall thereof, a plate slidably mounted in each container having a tongue projecting through said slot, a spring acting upon said plate, a latch mechanism operative upon each of said projecting tongues, a plurality of latch controlling pins slidably mounted in relation to said containers and each operative upon a latch mechanism, a spring operative upon each of said pins and having a normal tendency to position
90 said pins forwardly of said containers, whereby the actuation of said pins by engagement with a gun barrel will cause the selective or simultaneous release of said latch mechanisms, and means whereby said container may be attached to the wrist.

10. A shot gun loader embodying therein
100 two connected cylindrical shell containers, friction tongues extending inwardly of each container whereby falling of a shell from the container is prevented, each said container having a longitudinally extending slot
105 through the wall thereof, outwardly projecting laterally flared and transversely curved horns secured at the opposite sides of said containers, a plate slidably mounted in each container having a tongue projecting through said slot, a spring acting upon said plate, a latch mechanism operative upon each of said projecting tongues, a plurality of latch controlling pins slidably mounted in relation to said containers and each operative upon a latch mechanism, a spring operative upon each of said pins and having a normal tendency to position
110 said pins forwardly of said containers, whereby the actuation of said pins by engagement with a gun barrel will cause the selective or simultaneous release of said latch mechanisms, and means whereby said container may be attached to the wrist.

115 In witness whereof I have hereunto affixed
120 my signature this 1st day of March, 1932.

ANDREW ZICHY.
